(No Model.)

D. BROWN.

CARTRIDGE IMPLEMENT.

No. 340,549.

Patented Apr. 27, 1886.

UNITED STATES PATENT OFFICE.

DANIEL BROWN, OF JOHNSTON, RHODE ISLAND.

CARTRIDGE IMPLEMENT.

SPECIFICATION forming part of Letters Patent No. 340,549, dated April 27, 1886.

Application filed February 26, 1886. Serial No. 193,273. (No model.)

To all whom it may concern:

Be it known that I, DANIEL BROWN, of Johnston, in the county of Providence, in the State of Rhode Island, have invented a certain new and useful Improvement in Cartridge Implements; and I declare the following to be a specification thereof, reference being had to the accompanying drawings.

Like letters indicate like parts.

10 Figure 1 is a perspective view of the cartridge loaded and crimped by my improved cartridge-tool. Fig. 2 is a side elevation of my improved cartridge implement in use as a decapping-tool. Fig. 3 is a side elevation of 15 said implement in use as a cap-seating tool, the cartridge being shown in central vertical section. Fig. 4 shows, partly in side elevation and partly in central vertical section, said implement in use as a wad-seater. Fig. 5 shows, 20 partly in side elevation and partly in central vertical section, my said implement in use as a cartridge-shell crimper.

25 My invention is a combination-tool for capping, decapping, loading, and crimping paper or brass shot shells or cartridges; and it consists of a number of operative parts, which are capable of adjustment in various positions to adapt them to said operations, as hereinafter fully specified.

30 My improved cartridge-tool is made of four parts. A is the handle or knob, having a central bore, one at *a*, another in continuation thereof, but of smaller diameter, as shown at *b*, and a central conical bore, *c*, in continuation of the others, all fully illustrated in Fig. 4. B is a cylindrical block having a central bore, *d*, and another in continuation of it, but of smaller diameter, as shown at *e* in Fig. 4.

35 A screw, C, passes centrally through said block B, its slotted end being at the inner end of the bore *e*, and its outer end being countersunk, as seen in Fig. 4, and projecting centrally from the tapering end of the block B, as shown. A ferrule, D, surrounds the block 45 B. The rod E is a straight cylindrical stick having each end cut down to a smaller diameter to form circumferential shoulders *f g*. An expelling-pin, F, projects from one end of said rod E, as shown in Figs. 2 and 4. A metallic 50 tube, G, open at both ends, has a tapering circumferential shoulder or expansion, *h*, as fully

shown in Figs. 3, 4, and 5. At its smaller end it has an interior annular ring or lip, *m*.

The cartridge-shell on which this tool is intended to operate is also illustrated in the drawings in its several relations to and positions upon said tool. It is the common well-known shot-shell, consisting of a tubular portion, *n*, of paper or thin brass, with a metallic end or flanged portion, *o*, having a central cap-pock- 60 et, as shown in central vertical section in Figs. 3 and 5. It has the usual re-enforcing piece, *r*, with the interior annular projecting rim, and a central opening or fire-vent.

In Fig. 5, *s* represents the powder, *t* the wad 65 to confine the powder, *u* the shot, and *v* the wad to confine the shot.

The open end of the shell, when loaded, is crimped, as shown at *w* in Figs. 1 and 5, for the purpose of more firmly compressing and 70 confining the charge within the shell.

The operation of my improved cartridge-tool is as follows: To adapt the tool to remove the exploded cap from the shell after firing, insert the rod E through the tube, passing the 75 expelling-pin F through the smaller end of said tube. The shoulder *f* of the rod E then bears against the inner surface of the annular lip *m*. Then insert into the larger end of the tube G the smaller end of the block B, which will 80 receive in its central bore, *d*, the plain end of the rod E, and furnish a bearing for the shoulder *g* of said rod. Then insert the handle A into the projecting portion of the ferrule D of the block B. The tool as thus put together is 85 shown in Fig. 2. The cartridge-shell is then placed upon the tool when in the position shown in Fig. 2. As the tube G is of such a diameter as to closely fit into the tubular portion *n* of the shell throughout the length thereof, the expelling-pin F is truly centered in the shell, and accurately enters and passes through the vent of the re-enforcing piece *r* of the shell, and forces the cap out of the pocket. It is 90 most convenient to perform this operation by holding the shell upon the tool and striking the end of the handle A upon any suitable surface. The blow thus given readily expels the exploded cap from its seat in the pocket of the shell.

95 To adapt the tool to insert a new cap into the shell, enter the rod E into the bore *a* of

the handle A, with the pin F extending into said handle, as shown in Fig. 3. Then insert the block B into the tube G. The cartridge-shell is then slipped down over and upon the 5 rod E, the plain end of said rod entering within the rim of the re-enforcing piece r of the shell. Then bring down the parts B G over the head of the shell. While in the position as described, and with the left hand holding the 10 rod with the shell upon it, and the right hand holding the parts B G, as shown in Fig. 3, both hands are raised and brought down together, and the knob, on striking any hard substance, as wood, causes the cap-seating 15 screw to force the cap into the pocket of the shell.

To adapt the tool to seat the wads, insert the point end of the rod E into the bore d of the block B, (the pin F being received in the 20 bore e of said block.) Then insert the handle A into the ferrule D. Then slip the tube G over the rod E and block B. The tool is then used as an ordinary loading-stick, and is best shown in Fig. 4.

25 To adapt the tool to crimp the shell, I insert the smaller end of the tube G into the bore a of the handle A, and enter the open end of the cartridge-shell into the larger end of the tube G. As the tube G is pressed downward, 30 the end of the cartridge-shell is made to assume a smaller diameter by the contracted portion of the tube G at h, thus bending the shell inwardly around its entire circumference and forming the crimps or corrugations, w, which 35 are desired. The screw C, being adjustable, can be regulated to press the cap into the pocket to any required depth.

The peculiarity of my device is the reversibility of the rod E and tube G with reference 40 to the handle A and to each other, by means of which reversibility these few parts are brought into different positions and relations with each other, and are perfectly adapted to the several uses described.

45 This improved tool is cheaply constructed, simple in operation, compact in form, and without the levers or cumbersome appendages usually attached to such implements.

By the construction shown a plain circular 50 surface of sufficiently small diameter is provided at the end of the rod E to easily enter within the flanged rim of the re-enforcing piece r of the shell, as shown in Fig. 3, while by the insertion of the rod E within the tube

55 G, lipped at m, a broader end surface is obtained, which adapts it for forcing the wads accurately into the shell. I thus provide a

brass-bound loading-stick with metallic wearing-surfaces, yet light and compact and accurate in its fit within the shell. 60

The block B and the ferrule D can be made from one solid piece of wood or metal.

The improved tool may be used either with or without a common loading funnel and block.

I claim as a novel and useful invention and 65 desire to secure by Letters Patent—

1. The cap-expelling tool herein described, consisting of the handle A, the block B, having the ferrule D to receive said handle, the lipped tube G, fitted upon the block B, and 70 the shouldered rod E, inserted through said tube and engaged at one end within the bore d of the block B, and having at its opposite end the pin F, substantially as shown.

2. The wad-seating tool herein described, 75 consisting of the handle A, the block B, having the ferrule D to receive said handle, the lipped tube G, fitted upon the block B, and the shouldered rod E, having its plain end flush with the smaller end of the tube and its 80 pin-mounted end inclosed in the bores d e of the block B, substantially as described.

3. The cap-seating tool herein described, 85 consisting of the rod E, having the shoulder g and the centrally-bored handle A, to support the cartridge-shell and the tube G, the block B, the screw C, and the ferrule D, to fit over and upon the shell and seat the cap, substantially as specified.

4. In a combined decapping and cartridge-loading tool, the combination of the block B, having the central bores, d e, the reversible rod E, having the expelling-pin F and shoulders f g, and adapted to fit into and engage with the block B, the lipped tube G, mounted 95 upon the block B, and a suitable handle connected with said block, all arranged and operating substantially as specified.

5. The combined decapping, recapping, wad-seating, loading, and crimping-tool herein 100 described, consisting of the centrally-bored handle A, the centrally-bored block B, the screw C, centrally inserted in said block, the ferrule D, surrounding said block, the reversible and shouldered rod E, having the pin F, 105 the reversible and lipped tube G, with an expanded end from h, all arranged in the several relative positions and adapted to operate substantially as and for the purposes specified.

DANIEL BROWN.
